United States Patent Office

Des. 199,805
Patented Dec. 15, 1964

199,805

AIRCRAFT FUEL DISPENSER

Floyd E. MacSpadden, 13050 Memorial Drive,
Houston, Tex.

Filed Nov. 22, 1963, Ser. No. 77,543

Term of patent 14 years

(Cl. D52—2)

FIG. 1

FIG. 2

FIG. 3

FIG. 4

FIG. 5

FIG. 6

FIGURE 1 is a perspective view of the aircraft fuel dispenser, showing my new design;

FIGURE 2 is a right side elevational view thereof;

FIGURE 3 is a left side elevational view thereof;

FIGURE 4 is a rear elevational view thereof;

FIGURE 5 is a top plan view thereof; and

FIGURE 6 is a front elevational view thereof.

The bottom of the aircraft fuel dispenser, not shown in the drawings, is substantially plain in appearance.

The dominant features of the design are shown in full lines.

I claim:

The ornamental design for an aircraft fuel dispenser, as shown and described.
